A. Canfield.
Truss Bridge.

No

Patented Jun. 29, 1833.

Augustus, Banfield

The bridge referred to in these letters Patent and making part of the same containing a description in the words of the said Augustus Banfield himself of his improvement in the Construction of iron Bridges.

The upper horizontal pieces I call the upper strings, the lower horizontal pieces the lower strings, the upper pieces the posts. All these may be other chains or bars, the oblique pieces I call the braces. — The bars connecting the braces, the cross bars. — The pieces running from the upper cross bars to the lower — part of the post on the opposite side of the frame, the lateral braces. — The lower end of the braces rest on the foot pieces. — The pieces, bars &c are numbered from the abutments 1, 2, 3, &c. — The first upper strings are firmly attached to the abutments and to the head of the first brace. To the head of the first brace the head of the first post is attached & also the second upper string — To the foot of the first post is attached the first foot piece in which rests the foot of the second brace. — The head of the second brace is sustained by the second upper string running from the head of the first brace. The first foot pieces are presented from moving horizontally by the second lower strings &c so that when the bridge is up the upper strings are acted on by a direct tension from the abutments or the lower strings by a tension from the centre of the span. The floor timbers rest on bars or beams supported by the lower cross bars — The floor to be of either iron or wood. The lower springs between the abutment and the foot of the second brace may be put in or not as from a weight on the centre of the bridge there is no strain on them. And also the upper strings from the head of the outer braces to the next brace on each side,

for the same reason - This leaves every part of bridge
to contract or expand without any strain. I propose to
connect the parts but moved by a spiral spring that will
yield an inch or two under a tension of one or two tons.
Any number of strings and braces may be put in one
form or one side of the roadway. As in this construction
the stress upon each part by any given pressure is a matter
of simple calculation. As the contraction and expansion
are effectually provided for as the iron acts with its greatest
strength, viz., a strict tension or a strict tension, there being
not the slightest lateral strain & as it appears to possess
every requisite on a bridge. The Inventor believes this
to be the best arrangement of the materials that can
be made.
